ABSTRACT

An elevator system having an elevator car mounted for movement in the hoistway of a structure to serve the floors therein, and control mechanism for the elevator car which includes translating devices and tape mounted cams. Up to and including four lanes of cams are mounted on a single tape, and the required number of tapes are disposed in the hoistway and oriented in the travel direction of the elevator car. The translating devices, which are carried by the elevator car, are constructed and mounted to compensate for dimensional changes between the devices and tapes, to guide and exert centering forces on the tape, and to reduce operating noise between the tapes and its guides, and between the cams and the cam followers of the translating devices, by using guide and cam follower rollers biased against the edges of the tape.

ELEVATOR SYSTEM

BACKGROUND OF THE INVENTION

1. Field of the Invention:

The invention relates in general to elevator systems, and more specifically to elevator systems which utilize control mechanisms which include translating devices, such as electrical switches, and tape mounted cams, which cooperate to provide control signals responsive to the position of an elevator car in its hoistway.

2. Description of the Prior Art:

It is common in elevator systems of all types, including hydraulic, and both geared and gearless traction systems, to employ translating devices responsive to the position of an elevator car in its hoistway. The type of translating device employed depends to a large extent on the maximum normal operating speed of the elevator car. When the maximum car speed is about 350 feet per minute or less, cooperative cams and cam operated switches are usually used for the translating means because of their reliability and relatively low cost. When the normal car speed exceeds 350 feet per minute the noise created by the tape, upon which the cams are mounted, passing through the guides which properly locate the tapes and cams for the cam follower arms of the switches, and the noise of the cam follower rollers striking the cams, becomes objectionable. Thus, for car speeds above about 350 feet per minute, the translating devices commonly used are inductor relays. Inductor relays, and their application to elevator systems, are described in my U.S. Pat. No. 2,840,188, which is assigned to the same assignee as the present application.

While inductor relays are a desirable and a highly reliable form of control, their cost, as well as the cost of their associated control apparatus, is higher than cam-switch control arrangements, and it would therefore be desirable to be able to extend the usage of the cam-switch control arrangement to higher car speeds, such as to about 500 feet per minute, but the noise limitation associated with the cam-switch arrangements of the prior art will have to be overcome. In both the cam-switch and inductor relay arrangements, a separate tape with cams and magnetic plates, respectively, is used for each function. U.S. Pat. No. 2,938,603 discloses mounting cams between adjacent tapes. U.S. Pat. No. 1,360,420 illustrates an elevator system which uses cam-switch control. It would be desirable to reduce the number of tapes required in a cam-switch arrangement without reducing the number of different control functions.

SUMMARY OF THE INVENTION

Briefly, the present invention is a new and improved elevator system having an elevator car mounted for movement in the hoistway of a structure to serve the floors therein, and including control mechanism for controlling the elevator car. The control mechanism includes translating means in the form of electrical switches carried by the elevator car, and tape mounted cams in the hoistway, which cooperate to provide control signals responsive to the position of the elevator car in the hoistway. The control signals are used for such functions as stopping and leveling the elevator car at a landing.

Up to and including four different functions may be controlled with a single tape, as the cams are mounted

in spaced relation from both major surfaces or sides of the tape and adjacent both the right and left-hand edges thereof, to provide up to and including four lanes of cams per tape.

5 The switches each include guide and cam follower rollers, each of which control one of the two contacts of the switch. The guide and cam follower rollers are both biased against the same edge of the tape via a pivotal arrangement which allows the dimension between 10 the switch and the tape edge to vary within predetermined limits without adversely affecting the desired relationship between the two electrical contacts.

Movement of the cam follower roller without like 15 movement of the guide roller operates the electrical contact associated with the cam follower roller to change the relationship between the contacts.

Noise is substantially reduced by rotating both the guide and cam follower rollers against the tape edge when the elevator car is moving through the hoistway.

20 The cam follower roller is dimensioned such that it leaves the tape edge and rolls over the cams in its associated cam lane without interruption of its rotating mode. Thus, there is little noise between the rotating guide wheel, which is grooved to locate the tape in the direction of its thickness, and the tape, and since the cam follower roller does not strike a cam and then accelerate from zero RPM to an RPM dictated by car speed and roller diameter, but is already rotating when it rides up the inclined portion of a cam, noise due to 25 cam-switch engagement is also reduced.

30 Since a switch is required for each cam lane, the biasing forces of the guide and cam rollers are applied to both edges of the tapes, which provides a yieldable centering force on the tape in the direction of its width dimension.

BRIEF DESCRIPTION OF THE DRAWINGS

The invention may be better understood and further 40 advantages and uses thereof more readily apparent, when considered in view of the following detailed description of exemplary embodiments, taken with the accompanying drawings, in which:

45 FIG. 1 is a diagrammatic view in elevation of an elevator system embodying the teachings of the invention;

FIG. 2 is a perspective view, with parts broken away, illustrating four cam lanes per tape, in accordance with the teachings of the invention;

50 FIG. 3 is an elevational view illustrating switches constructed according to the teachings of the invention, and also illustrating the mounting of a plurality of switches relative to a tape;

FIG. 4 is a side elevation of the switch arrangement shown in FIG. 3;

FIG. 5 is a fragmentary plan view of the switch arrangement shown in FIG. 3;

FIG. 6 illustrates the self compensating feature of one of the switches shown in FIG. 3, for a variation in the dimension between the switch and the tape; and

60 FIG. 7 illustrates cam actuation of one of the switches shown in FIG. 3.

DESCRIPTION OF PREFERRED EMBODIMENTS

Referring now to the drawings, and FIG. 1 in particular, there is shown an elevator system 10 constructed according to the teachings of the invention. While the elevator system 10 is illustrated as being of the traction

type, the invention is equally applicable to hydraulic elevator systems.

More specifically, elevator system 10 includes an elevator car 12 mounted for movement in a hoistway 14 of a building or structure 16 having a plurality of floors or landings, indicated generally at 18, which floors are served by the elevator car 12. An elevator drive motor 20, which may be disposed in the penthouse 22 of the building 16, drives a traction sheave 24 via a drive shaft 25. When the invention is applied to elevator systems having a maximum car speed of about 350 feet per minute or less, the drive motor 20 will conventionally drive the sheave through a gear reducing mechanism (not shown).

Hoisting ropes or cables 26 interconnect the elevator car 12 with a counterweight 28, with the ropes 26 extending from the car 12, about the traction sheave 24, and then to the counterweight 28.

Signals responsive to the position of the elevator car 12 in the hoistway 14, which signals are used to control the movement, deceleration and landing of the car 12, are provided by a control mechanism which includes one or more elongated control elements, such as control elements 30 and 32, which extend along the hoistway 14 in the direction of movement of the car 12. The elongated control elements 30 and 32 are each continuous from a point below the lower end of the path of travel of the elevator car 12 to a point above the upper end of its travel path.

The control elements 30 and 32 are guided with respect to a control unit 34 which is mounted on the elevator car 12. The upper ends of the control elements 30 and 32 are secured to the building or structure 16, as indicated at 36, and its lower ends pass through a fixed guide 36 and are then tensioned by any suitable means, such as by weights 38, or by springs.

Each of the control elements 30 and 32 are constructed of inextensible magnetic, or non-magnetic metallic material, or non-metallic material, as desired. Steel, for example, is excellent, but other materials may be used.

As shown more clearly in FIG. 2, which is a perspective view of control element 30, each control element is preferably in the form of a metallic ribbon or tape having first and second flat, major opposed surfaces or sides 40 and 42, respectively, and first and second edges 44 and 46, respectively. Each control element or tape, such as tape 30, preferably has a plurality of vertically spaced, elongated slots 48 formed therein to facilitate attaching cam members thereto, which will be hereinafter described. The length of the slots is greater than the spacing between slots, to permit unlimited adjustment of the cam devices connected thereto.

Each tape or control element may have up to and including four cam lanes associated with it, for providing signals responsive up to and including four different functions. As best illustrated in FIG. 2, the cams are mounted adjacent both major surfaces 40 and 42, and the cams on each side of the tape are disposed adjacent to both the first and second edges 44 and 46, thus providing right and left front cam lanes, and right and left rear cam lanes.

A single cam member having two cam profiles may be used to provide cams in the two lanes adjacent one major surface of the tape, when two cams are to be located in side by side relationship, a cam member may have a single cam profile when used for a single cam

lane, or both types of cam members may be used, as required by a specific application. For purposes of example, two cam members 50 and 52 are illustrated in FIG. 2 for providing the four cam lanes, with each cam member having two cam profiles for the cam lanes on its side of the tape 30.

Each of the cam members 50 and 52 are formed to provide the desired cam profiles, and the cam profiles are oriented to move a cooperative cam follower in a direction which is substantially parallel to the major opposed surfaces 40 and 42 of the tapes 30, and thus the direction which the cam followers are moved is substantially perpendicular to the edges of the tape.

For purposes of example, cam members 50 and 52 are illustrated as being constructed from a relatively thin, elongated metallic plate member, such as steel. Cam member 52 has first and second major opposed surfaces 54 and 56, respectively, and first and second edges 58 and 60, respectively. The cam profiles are formed on the edges 58 and 60. Cam member 50 has first and second major opposed surfaces 62 and 64, respectively, and first and second edges 66 and 68, respectively. The cam profiles are formed on the edges 66 and 68. Thus, edges 58 and 60 provide cams in the left and right front cam lanes, respectively, and edges 66 and 68 provide cams in the left and right rear cam lanes, respectively.

The cam members 52 and 50 are mounted in predetermined spaced relation from the major opposed surfaces 40 and 42, respectively, of tape 30, such as by inserting tubular spacer members 70 and 72 between the cam member 52 and the major surface 40 of the tape 30, which tubular spacer members have their openings aligned with openings disposed through the cam members and with a slot 48. Nut and bolt combinations shown generally at 74 and 76 may then be used to firmly secure the cam members 52 and 54 in spaced relation with the major opposed surfaces 40 and 42, respectively, of the tape 30.

As best illustrated in FIG. 7, which is a front elevational view of tape 30 and cam member 52, each of the cam profiles start in alignment with an edge of the tape 30, they taper outwardly to the maximum dimension of the cam profile, the maximum dimension is retained for a predetermined dimension, and then the profile tapers inwardly until it is again in alignment with the same edge of the tape 30. For example, the cam profile in the right front cam lane starts at point 78, which point is in the same plane as edge 46 of tape 30, it tapers outwardly along portion 80 and flows smoothly into the surface 82 which is the maximum dimension of the cam profile measured outwardly from point 78. This maximum dimension, as defined by surface 80, is retained for a predetermined dimension and then the cam profile flows smoothly into tapered portion 84, with the taper ending at point 86, which point is again in the same plane as edge 46 of the tape 30.

Each cam lane requires a translating device which is responsive to the position of the cams in its lane. Since each tape supports four cam lanes, four translating devices may be associated with each tape, if all four lanes are utilized. Thus, since two tapes 30 and 32 are illustrated in FIG. 1, which provides up to and including eight cam lanes, as many as eight translating devices would be mounted in the control unit 34 shown in FIG. 1.

FIG. 3 is a front elevational view of one of the tapes, such as tape 30, illustrating first and second translating devices or switches 100 and 102, respectively, for co-operating with two of the cam lanes. Since the translating devices are of like construction, with only their orientation being different for the various cam lanes, only translating device or switch 100 will be described in detail. FIGS. 4 and 5, which are side and plan views of the switch 100, respectively, will also be referred to when describing the construction of the switch 100.

Translating device 100 is an electrical switch oriented to be responsive to the cams in the left front cam lane. Switch 100 includes a mounting base 104, which may have a configuration in the form of an elongated rectangle, as illustrated, having first and second major opposed surfaces or sides 105 and 107, respectively. Base 104 is secured to a suitable mounting bracket 106, shown in FIGS. 4 and 5, such as by screws 108 and 110. First and second bearing members 112 and 114, respectively, are fixed in spaced relation through openings disposed through the mounting plate 104 and mounting bracket 106. Shaft members 116 and 118 are journaled for rotation in bearings 112 and 114, respectively, with the shaft members 116 and 118 extending outwardly from both ends of their associated bearings. The longitudinal axes of shaft members 116 and 118 are parallel with one another, and substantially perpendicular to the major opposed surfaces of the mounting plate member 104.

Cam and guide arm members 120 and 122 are fixed to the ends of shaft members 116 and 118, respectively, which ends extend outwardly from bearings 112 and 114, respectively, adjacent to the side 107 of the mounting plate member 104. Cam and guide arm members 120 and 122 are of like configuration and construction, but are oriented differently, with one being rotated 180° with respect to the other, and then flipped over. Cam and guide arm members 120 and 122 include first projections 124 and 126, respectively, which function as spring seats, second projections 128 and 130, respectively, which cooperate to function as a stop, and third projections 132 and 134, respectively. The third projections 132 and 134 support shaft members 136 and 138, respectively, which extend outwardly in a common direction away from the mounting plate 104. Shaft members 142 and 144 are attached rigidly to shaft members 136 and 138, respectively. Shaft members 142 and 144 extend outwardly from members 136 and 138, and journal the rollers 146 and 148 for rotation.

As illustrated most clearly in FIG. 4, the outer periphery of the guide roller 148 has a vee groove 150 disposed therein, with the width dimension of groove 150 being selected to accommodate the width dimension of the tape 30. The width dimension of groove 150 in the guide wheel is selected to accurately locate and guide the tape 30 in the direction of its thickness. Also, as illustrated most clearly in FIG. 4, the cam follower roller 146 has a smooth, relatively wide outer surface, a portion of which is aligned with the groove 150 in the guide roller, as indicated by broken line 155. A portion of this outer surface extends from the broken line 155 towards the cam arm 120, for engaging the cams in its associated cam lane.

The projections 124 and 126 of the cam and guide arms 120 and 122, respectively, which function as spring seats, may have pins 152 and 154 disposed

through suitable openings therein, and a compression spring member 156 is disposed between the spring seats and pins 124, 152 and 126, 154. Compression spring 156 rotates cam arm 120 clockwise about shaft 116, and guide arm 122 counterclockwise about shaft 118, until projections 128 and 130 contact one another to provide a stop.

First and second contact finger board members 160 and 162, which are of like construction, are fixed to the ends of shaft members 116 and 118 which ends extend outwardly from side 105 of the mounting plate member 104. The contact finger boards 160 and 162 each have a curved portion which has the same radius as its associated shaft, and a screw disposed through the curved portion threadably engages a tapped opening in the shaft to secure each contact finger board member to the side of its associated shaft member. For example, screws 164 and 166 extend through the curved mounting portions of finger board members 160 and 162, respectively, to mount the finger board members to shaft members 116 and 118. Thus, pivotal movement of cam follower roller 146 on its guide arm 120 about the longitudinal axis of shaft 116 rotates shaft 116 and also the finger board member 160. In like manner, pivotal movement of guide roller 148 on its guide arm 122 rotates shaft member 118 and the finger board member 162.

In addition to the curved mounting portions, each finger board member has first, second and third projections, best shown in FIG. 4, with finger board member 160 having first, second and third projections 168, 170 and 172, respectively, and finger board member 162 has first, second and third projections 174, 176 and 178, respectively.

The projections 168 and 172 each define substantially U-shaped channels, and a first flexible metallic electrical contact member 180, having a contact button 182 fixed to one end thereof, is disposed to lie flat in these two U-shaped channels, oriented with its contact button 182 on its lower end facing to the left when viewing switch 100 in FIG. 3. Projection 170 has a raised spring seat button 184 facing the contact member 180, and a compression spring member 186 is disposed from the spring seat button 184 to the electrical contact, to bias the contact member 180 outwardly to snugly hold the contact member in the channels defined by the projections 168 and 172 on the finger board member 160.

In like manner, a contact member 188 having a contact button 190 on one end thereof is secured to finger board member 162 by a compression spring 192. Contact member 188 is oriented such that its contact button is on its upper end, on the side thereof facing to the right, when viewing switch 100 in FIG. 3.

As illustrated in FIG. 3, switch 100 is mounted such that spring 156 biases rollers 146 and 148 snugly against edge 44 of tape 30. Biasing the rollers against the tape edge 44 compresses the spring 156 and provides a gap 194 between the projections 128 and 130, which projections cooperate to provide a stop. The correct amount of initial bias, when tape 30 is properly centered in the direction of its width, is when the longitudinal axes of electrical contact members 180 and 188 are both substantially parallel with one another. It will be noted that both the cam follower and guide rollers 146 and 148 are biased against the same edge 44 of the tape 30. It will also be noted in FIG. 5, which illustrates

the cam members 50 and 52 mounted on the tape 30 below the present location of switches 100 and 102, that the width of the cam follower roller 146 is sufficient to contact the edge 44 of tape 30, and also to contact the cam profile located in the left front cam lane. It will be noted that the roller will not contact the cam profile in the left rear cam lane.

Reorienting switch 100 from the position shown in FIG. 3 by rotating it 180° about a horizontal axis in the plane of the drawing will orient it for the right front cam lane, now occupied by switch 102 in FIG. 3. Switches oriented similar to switches 100 and 102 will service the left and right rear cam lanes by reversing the orientation of the cam follower roller as it is placed into position on shaft 142. The construction of the cam follower roller 146 which provides this result is best shown in FIG. 5.

Since the switches 100 and 102 are biased against opposite edges 44 and 46 of the tape 30, they exert a yieldable centering force on the tape 30. When locating the switches in pairs on the tape, if they are centered on the tape they will exert the same force on the tape. If they are not centered on the tape, one switch will exert more force on one side of the tape, the other switch less force on the other side of the tape. The switches exert a gentle pressure to center the tape while still adapting to the off-center tape. The further off center, the higher the centering pressure on the tape. While the grooved guide rollers 148 locate the tape 30 accurately in the direction of its thickness, the tape 30 may move slightly in the direction of its width, even though under the influence of the centering forces provided by the biased rollers against opposite edges of the tape. The pivotal arrangement of the cam follower and guide rollers 146 and 148, respectively, with each roller controlling the position of an electrical contact, automatically compensates for changes in the location of tape 30 in the direction of its width. This automatic compensating feature for an off-center tape is illustrated more clearly in FIG. 6, which illustrates switch 100 in solid lines when the tape 30 is correctly centered in the direction of its width, and the switch 100 is shown in phantom or broken lines to illustrate the edge 44' of an off-center tape which has moved edge 44 closer to the switch 100. When the tape edge moves closer to the switch 100, it compresses spring 156 to a greater extent, to increase the centering force applied to edge 44 of the tape 30, it rotates cam arm 120 counterclockwise about shaft 116, moving contact 180 counterclockwise, and it rotates guide arm 122 clockwise about shaft 118, moving contact 188 clockwise by the same amount that contact 180 moved counterclockwise, maintaining the predetermined relationship of the contacts, which, as illustrated in the example of switch 100 shown in FIG. 3, is the closed condition. If edge 44 were to move from the solid line location to the right, instead of to the left as shown in FIG. 6, spring 156 would be subjected to less compression, reducing the magnitude of the centering force on edge 44 of the tape. Cam arms 120 and 122 would rotate electrical contacts 180 and 188 clockwise and counterclockwise, respectively, by the same increment, to maintain the same relative positions of the contacts as when the tape 30 is correctly centered in the direction of its width dimension.

FIG. 7 is an elevational view of switch 100 which illustrates actuation of the switch by the cam profile of

cam member 52 which is located in the left front cam lane. The rotating guide roller 148 remains on the edge 44 of the tape 30, while the rotating cam follower roller 146 continues to rotate as it is lifted off of the edge 44 of the tape 30 by the cam profile. The cam profile causes the cam roller 146 to pivot the cam arm 120 counterclockwise about shaft 116, moving electrical contact member 180 counterclockwise and out of engagement with electrical contact 188. When the cam follower roller 146 returns to the edge 44 of the tape 30, electrical contact 180 will move clockwise, back into engagement with electrical contact 188.

In summary, there has been disclosed a new and improved elevator system of the type in which the position of an elevator car in its hoistway is monitored by switching devices carried by the car which cooperate with tape mounted cams disposed in the hoistway. For example, in the disclosed elevator system there is no sliding contact between guides and their tapes, with all of the guiding contacts being rotational, the switching devices responsive to the cams are disposed and constructed to provide yieldable centering forces on the tapes in the direction of its width, the disclosed switches automatically compensate for an off-center tape, maintaining the same relative position for the contacts when the tape is off center, as well as when the tape is on center, the cam follower roller is already rotating at the correct speed when it encounters a cam profile to reduce the cam follower roller—cam contact noise level, and the number of tapes required to be mounted in the hoistway is substantially reduced, since each tape is capable of handling up to and including four cam lanes.

I claim as my invention:

1. An elevator system, comprising:
a structure having a plurality of floors and a hoistway,

an elevator car,

means mounting said elevator car for movement in said hoistway to serve at least certain of said floors,

control means for said elevator car including an elongated member having first and second substantially opposed surfaces and first and second edges, a first cam member having a first cam profile thereon, and means mounting said first cam member on said elongated member in spaced relation relative to the first opposed surface and with the first cam profile oriented to move a cooperative cam follower in a direction substantially parallel with the first opposed surface,

means mounting the elongated member of said control means to extend along the hoistway of said structure in the direction of movement of said elevator car,

translating means including a first switch device having a cam follower and guide means, and means mounting said translating means on said elevator car,

said guide means being disposed to guide said control means adjacent to said first switch device such that the cam follower of said first switch device is responsive to the first cam profile of said first cam member.

2. The elevator system of claim 1 wherein the first cam profile of the first cam member extends outwardly past the first edge of the elongated member.

3. The elevator system of claim 2 including a second cam member having a first cam profile thereon, means mounting said second cam member on the elongated member in spaced relation relative to the first opposed surface thereof, with the first cam profile of said second cam member extending outwardly past the second edge of the elongated member, and wherein the translating means includes a second switch device having a cam follower and guide means mounted such that the cam follower of the second switch device is responsive to the first cam profile of the second cam member.

4. The elevator system of claim 2 wherein the first switch device includes first and second electrical contacts, the guide means includes a guide roller, and the cam follower includes a cam follower roller, and including means interconnecting said guide and cam follower rollers with said first and second electrical contacts, respectively, and means biasing said guide and cam follower rollers in opposite circumferential directions about first and second pivot axes against the first edge of the elongated member, to compensate for a change in the dimension between the switch and the edge of the tape, and prevent relative movement between the first and second electrical contacts while both the guide and cam follower rollers are in contact with said common edge of the elongated member.

5. The elevator system of claim 4 wherein the cam follower roller has a width dimension selected to enable it to rotate on the first edge of the elongated member until coming to the first cam profile, at which point the cam follower roller leaves the first edge of the elongated member and follows the cam profile while continuing to rotate.

6. The elevator system of claim 4 wherein the axes of the guide and cam follower rollers are disposed in spaced parallel relation, and the first and second pivot axes are located between the axes of the guide and cam follower rollers.

7. The elevator system of claim 4 including a second cam member having a first cam profile thereon mounted in spaced relation relative to an opposed surface of the elongated member, with the cam profile extending outwardly past the second edge of the elongated member, and including a second switch device constructed similarly to the first switch device, and including means biasing the second switch device against the second edge of the elongated member, to locate the elongated member between the first and second switch devices in the direction perpendicular to its first and second edges, with yieldable centering forces.

8. The elevator system of claim 1 wherein the first cam member includes a second cam profile which extends outwardly in a direction opposite to the first cam profile to establish first and second different cam lanes on one side of the elongated member, and wherein the translating means includes a second switch device having a cam follower and guide means mounted such that the cam follower of the second switch device is responsive to the second cam profile of the first cam member.

9. The elevator system of claim 8 wherein the first and second cam profiles extend outwardly past the first and second edges, respectively, of the elongated member.

10. The elevator system of claim 1 including a second cam member having a first cam profile thereon, means mounting said second cam member on the elongated

member in spaced relation relative to the second opposed surface thereof, with the first cam profile of said second cam member oriented to move a cooperative cam follower in a direction substantially parallel with the second opposed surface, and wherein the translating means includes a second switch device having a cam follower and guide means mounted such that the cam follower of the second switch device is responsive to the first cam profile of the second cam member.

11. The elevator system of claim 10 wherein the first and second cam members each have first and second oppositely extending cam profiles thereon, which extend outwardly past the first and second edges, respectively, of the elongated member to establish four different lanes of cams, and wherein the translating means includes third and fourth switch devices each having cam follower and guide means mounted such that the cam follower of the third and fourth switch devices are responsive to the second cam profiles of the first and second cam members, respectively.

12. The elevator system of claim 1 wherein the guide means is a guide roller adapted to ride on an edge of the elongated member.

13. The elevator system of claim 12 wherein the guide roller is grooved to accommodate an edge of the elongated member and provide a guide for the elongated member in the direction between its first and second opposed surfaces.

14. The elevator system of claim 1 wherein the cam follower is a roller and the first cam profile extends outwardly past the first edge of the elongated member, and wherein the cam follower roller has a width dimension selected to ride against the first edge of the elongated member until coming to a cam profile at which point it leaves the edge of the elongated member and follows the cam profile.

15. An elevator system, comprising:

a structure having a plurality of floors and a hoistway,

an elevator car,

means mounting said elevator car for movement in said hoistway to serve at least certain of the floors,

control means for said elevator car including a tape member having first and second flat major opposed surfaces and first and second edges, and a plurality of cam members fixed in spaced relation to opposite major opposed surfaces of said tape member, certain of which extend past the first edge of the tape member, and certain of which extend past the second edge of the tape member, from both major opposed surfaces of the tape member, to define four lanes of cam members,

means mounting the tape member to extend along the hoistway of said structure in the direction of movement of said elevator car,

translating means including four switch devices, one for each of said four cam lanes,

means mounting said translating means on said elevator car,

each of said switch devices including a guide roller and a cam follower roller, and means biasing said guide and cam follower rollers for rotation against a common edge of said tape member, with two of said switch devices having their guide and cam follower rollers biased against the first edge and two

11

of said switch devices having their guide and cam follower rollers biased against the second edge.

16. The elevator system of claim 15 wherein the guide rollers are grooved to guide the tape member in the direction between its first and second major opposed surfaces, and the switch devices, being biased against the first and second edges, provide yieldable centering forces to locate the tape member in the direction between its first and second edges.

17. The elevator system of claim 15 wherein the width dimension of the cam follower rollers of the switch devices is selected to enable each roller to rotate against an edge of the tape member until reaching a cam member in its associated lane of cam members, at which point the cam follower roller rides up the profile of the cam member while continuing to rotate.

18. The elevator system of claim 15 wherein the means biasing each of the switch devices against an edge of the tape member biases the guide and cam follower rollers of each switch device in opposite circumferential directions about first and second pivot axes

12

disposed between the axes of the guide and cam follower rollers, and including first and second electrical contacts responsive to the pivoting of the guide and cam follower rollers, respectively, with pivoting of both rollers due to changing spacing of the switch device and the adjacent edge of the tape member maintaining the first and second electrical contacts in the same relative position to one another, and the pivoting of only the cam follower roller when the cam follower roller follows the cam profile changes the position of its associated electrical contact relative to the other electrical contact.

19. The elevator system of claim 15 wherein the cam follower rollers are constructed such that a first orientation thereof relative to its associated switch device will accommodate the cam lanes adjacent one major surface of the tape member, and a second orientation, which is opposite the first orientation, will accommodate the cam lanes adjacent the opposite major surface of the tape member.
